UNITED STATES PATENT OFFICE.

THOMAS J. MAYALL, OF READING, MASSACHUSETTS.

RUBBER OVERSHOE.

SPECIFICATION forming part of Letters Patent No. 228,769, dated June 15, 1880.

Application filed April 15, 1880. (Model.)

To all whom it may concern:

Be it known that I, THOMAS J. MAYALL, of Reading, Massachusetts, have invented a new and useful Improvement in India-Rubber Over- 5 shoes, of which the following is a specification.

The object of my invention is to provide a water-proof overshoe so light and made in such form that the pair can be rolled up like a pair of gloves in a package so small that it 10 can be conveniently carried in the pocket.

My invention relates to the thickness of the rubber sheet and the shape and relation to each other of the several pieces which make up the shoe.

15 To make this overshoe, pure rubber of a high quality should be used. For the bottom of the shoe I make it about one thirty-second part of an inch thick, and for the top about half as thick as the bottom, the heel being 20 overlaid with one thickness.

A piece of rubber sheet is cut out for the bottom of the shoe. A piece of rubber sheet for the top or vamp is cut out in the same form as for the bottom, but a little larger, and at 25 the heel the breadth and length are increased beyond that of the sole and heel considerably more than forward of the shank. The edges of the piece cut out for the top or vamp are folded in and cemented to the bottom or 30 sole. The piece of rubber for the top or vamp is cut open on a central line from a point about one and three-quarters inch from the forward end to a point about one and one-half inch from the rear end. Along each side of this

35 cut, and around the ends of it, I lay a re-enforcing-strip of the rubber sheet about half an inch wide, which is cemented to its place. From the rear end of the cut mentioned to the rear end of the shoe, and lapping over onto 40 the heel, I also lay a re-enforcing-strip of rubber sheet, which is cemented to its place. At the rear end of the cut in the top or vamp this last-mentioned re-enforcing-strip is lined with cloth and formed into a loop, through

45 which a tape or string is passed loosely, and in wearing the shoe the tape is brought forward around the ankle and tied over the instep to prevent the shoe from slipping off at the heel.

50 The object of lining the re-enforcing-strip with cloth is to make it non-elastic, and to pre-

vent the tape or string from wearing or breaking out the loop. I also place a re-enforcing-patch on the inside of the shoe at each end of the cut in the top or vamp to prevent tearing 55 when the shoe is drawn on the foot.

The shoe being thus prepared and made is then vulcanized in the usual manner, and is complete and ready for use. The top or vamp will, except at the heel, lie flat upon the sole, 60 and the vulcanizing is done when it is upon a form of which the forward part is as thin as it can be made and keep its shape, while at the heel it is thicker, about three-quarters of an inch, and rounded on the upper side. 65

The cut in the top or vamp is to make the opening for the foot to enter, and the elasticity of the rubber gives space for it, and at the same time makes the whole shoe cling closely to the foot or the boot or shoe over which it 70 is worn, so that water cannot get in between the overshoe and the inner one. Thus I produce a pair of overshoes weighing from two to four ounces, according to size, and which can be rolled up together in a cylindrical 75 bundle about an inch to an inch and a half in diameter and about three inches long. I make a small pouch of elastic sheet-rubber, in which the pair of overshoes so rolled up are placed and secured by an elastic band or otherwise.

In the drawings annexed, Figure 1 shows an overshoe lying on its bottom on a flat surface. Fig. 2 shows a side view of an overshoe as it appears in use on the foot. Fig. 3 shows 85 the pouch. Fig. 4 shows the pair of overshoes rolled up in a bundle ready to be placed in the pouch.

a is the top or vamp of the overshoe. *c* is the re-enforcing-strip. *d* is the cut in the top 90 or vamp. *e* is the loop for the fastening-tape. *g* is the tape in the loop.

Having thus described my invention, I claim as new—

1. An overshoe composed of thin sheets of 95 rubber substantially without backing or lining united in their plastic condition, as described, so that when vulcanized the shoe shall be practically flat and elastic in all directions, as and for the purposes set forth. 100

2. In a rubber overshoe, the top or vamp composed of a thin elastic sheet, and provided

with an opening for the foot formed by a slit or cut in said top or vamp, substantially as described.

3. In an overshoe having an elastic top or vamp, the combination, with said top or vamp, of a re-enforcing-band secured at the back of the heel, substantially from the top to the bottom, and provided at its upper end with a small loop for the reception of a string or securing-band, as set forth.

4. An overshoe formed mainly of two sheets of elastic india-rubber, constituting the sole

and top or vamp, respectively, with a straight slit or cut in said top or vamp to form the opening for the foot, the shoe being also provided with re-enforcing-strips around said opening and at the back of the heel, and the whole being cemented and vulcanized, substantially as described.

THOS. J. MAYALL.
